DESIGN FOR AN AUTOMOBILE GRILLE
PANEL

Robert Cadwallader, Detroit, Mich., assignor to Chrysler Corporation, Highland Park, Mich., a corporation of Delaware

Application December 29, 1945, Serial No. 125,133

Term of patent 7 years

(CL. D14—18)

To all whom it may concern:

Be it known that I, Robert Cadwallader, a citizen of the United States, residing in the city of Detroit, county of Wayne, and State of Michigan, have invented a new, original, and ornamental Design for an Automobile Grille Panel, of which the following is a specification, reference being had to the accompanying drawing, forming part thereof, in which:

Fig. 1 is a front elevational view of the automobile grille panel showing my new design;

Fig. 2 is a top plan view of the same;

Fig. 3 is a side elevational view thereof looking at the right side of Fig. 1.

I claim:

The ornamental design for an automobile grille panel, substantially as shown.

ROBERT CADWALLADER.
